LATCHING MECHANISM

Harry F. George, Park Ridge, Ill.

Application April 1, 1957, Serial No. 649,840

2 Claims. (Cl. 292—341.17)

This invention relates to improved latching mechanism, including a novel striker plate, for doors and structures of a similar nature, and while especially useful for screen doors, it is to be understood that the same may be applied to any other type of door or similar structure, either wood or metal, to which it may be adapted.

The present invention is an improvement over those disclosed in my Patent No. 2,835,125, granted May 20, 1958 and U.S. Patents Nos. 2,764,014 granted to me September 25, 1956, 2,801,869 granted to me August 6, 1957, and 2,803,957 granted to me August 27, 1957.

The latching mechanism of the present invention is made up of a small number of parts, and lends itself to low cost manufacturing and easy assembly, as well as efficiency in operation. An important feature of the invention is the provision of a novel striker plate that, when the door is latched shut, may be easily manually operated from the inside by swinging a spring biased plate to clear the latching nose to enable the door to be swung open, or the door may be opened by rotating the main shaft to swing the latching nose clear of the striker plate. Also embodied in the latching mechanism are means operable from the inside of the door for locking the main shaft against rotation, and unlocking the same, from the inside when desired.

Among the objects of the invention are: to provide a new and improved latching mechanism and striker plate; to provide a striker plate having a swingable plate pivoted at one edge and depressible at the opposite edge, and spring biased to normally hold the swingable plate at an angle to the door frame; to provide an improved striker plate having a swingable plate and a novel mounting for swingably supporting the same on a door frame; to provide a striker plate having a swingable plate and supporting frame, the supporting frame being adjustably mountable with relation to a door frame; to provide latching mechanism having a main shaft, an adjustable latching nose, and turning members fixed thereto, and novel means for mounting the main shaft and turning members to a door or the like; to provide improved latching mechanism having manually operated means for locking and unlocking a door or the like from the inside of the door, when the door is in closed position; to provide latching mechanism of few parts, and which is economical to manufacture, easy to assemble, and effective in operation; to provide latching mechanism that may be factory assembled, turns left or right, may be applied to left and right hand doors of either metal or wood, that requires no mortising of the door, and is easy and quick to apply to the door; and such further objects, advantages and capabilities, inherently possessed by my invention, as will later more fully appear.

My invention further resides in the combination, construction and arrangement of parts illustrated in the accompanying drawings, and while I have shown therein preferred embodiments I wish it understood that the same are susceptible of modification and change without departing from the spirit of the invention.

2

In the drawings,

Fig. 1 is a top plan view of a portion of a door and door frame, having my invention applied thereto, and showing in full lines the door in closed and latched position, and in dotted lines the door in partially open position.

Fig. 2 is a side elevation looking toward the inside of the door, and showing in full lines the door in closed and latched position, and showing in dotted lines the inside handle member swung to two positions for releasing the latching nose from the striker plate to permit the door to be opened.

Fig. 3 is an enlarged, fragmentary, horizontal section on the line 3—3 of Fig. 2.

Fig. 4 is a vertical, transverse section on the line 4—4 of Fig. 3.

Fig. 5 is a fragmentary, vertical, longitudinal section on the line 5—5 of Fig. 4.

Fig. 6 is a vertical, transverse section through the latching mechanism, on the line 6—6 of Fig. 3, and showing the locking means in unlocked position.

Fig. 7 is a fragmentary, sectional view similar to Fig. 6, but showing the locking means in locked position.

Fig. 8 is a front elevation of the striker plate.

Fig. 9 is an enlarged detail face view of a spring washer having detents for releasably holding the housing member and shaft in locked and unlocked positions.

Fig. 10 is an edge view of Fig. 9.

Fig. 11 is an enlarged, vertical section on the line 11—11 of Fig. 1.

As shown in the drawings, my invention comprises, in general, a main shaft 1, an inner handle 2, an outer handle or knob 3, a base plate 4, a housing member 5 for housing a biasing spring 6, a detent washer 7, a retaining washer 8, and a striker plate indicated generally at 9.

The main shaft 1 is formed at its inner end with an enlarged portion 10 from which extends a portion 11 of square cross section. The square portion 11 of the main shaft extends to within the hollow interior of the housing member 5 from which it extends axially as a portion 12

with a round cross section to pass rotatably through a hole 13 in the door 14. The main shaft 1 after passing through the door, extends through a complementary opening in the outer handle 3, to which it is fixed by a nut 15 threaded onto threads 16 formed on the adjacent end of the main shaft 1. The nut 15, seated in a hollowed-out cavity c in the knob 3, enables adjusting the length of the shaft for different door thicknesses, these parts being adjusted to the desired tightness, but permitting rotation of the main shaft. The knob 3 and that portion of the main shaft extending thereto may be further fixed to rotate together by providing a flattened portion on the shaft, and a complementary flattened side in the opening in the knob 3, if desired. A dress-up cap 17 is pressed into the outer end of the cavity c after the complete assembly is attached to the door.

The inner end of the main shaft 1 is secured in the inner handle 2 by a press fit, thus avoiding the necessity of securing this end of the main shaft in the handle by casting which would slow down the molding operation. The base plate 4 is provided with a pressed-up portion forming a circular flange 18 of sufficient depth to provide space for the retaining washer 8 which is formed with a radially extending slot 19 to enable the retaining washer to be pushed into the circumferential groove 20 formed in the round part 12 of the main shaft at a location flush with the inner face of the door to position the main shaft and retaining washer 8 as shown in Figs. 3 and 5. The base plate 4, as seen in Figs. 5 and 6, is formed with upwardly and downwardly extending ears 21 and 22 to come flush with the inner face of the door, which ears each have a suitable hole to receive a screw or the like 23 to be screwed into the door. This enables the base

of the base plate 4 to be secured to the door frame, and the base plate 4 to be secured to the door.

The housing member 5 is formed with a base 24 having a slot 25 formed therein to receive the retaining washer 8, and a top 26 having a slot 27 formed therein to receive the biasing spring 6. The housing member 5 is formed with a base 24 having a slot 25 formed therein to receive the retaining washer 8, and a top 26 having a slot 27 formed therein to receive the biasing spring 6.

The biasing spring 6 is formed with a central portion 28 having a slot 29 formed therein to receive the retaining washer 8, and a top 30 having a slot 31 formed therein to receive the biasing spring 6.

The retaining washer 8 is formed with a central portion 32 having a slot 33 formed therein to receive the biasing spring 6, and a top 34 having a slot 35 formed therein to receive the biasing spring 6.

plate to be secured to the inner face of the door, and hold the retaining washer 8 flush thereto without mortising or forming any recess in the door. An inwardly extending finger 24, see Figs. 5 and 6, is struck up from the metal of the base plate 4, to stand midway and on the upper side of the opening 25 formed in the elevated portion of the base plate. Opening 25 is extended arcuately a distance laterally in both directions, as will be understood in Figs. 6 and 7.

The housing member 5 is cup shaped and is formed with a circumferentially extending flange 26 which slidably bears against the elevated portion of the base plate 4. The elevated circular wall of the housing member 5 is formed with an elongated rectangular opening 27 of a width slightly greater than the lateral thickness of the square portion 11 of the main shaft, and of a length sufficiently greater than the cross dimension of said square portion to permit the cup shaped housing member 5 to slide up and down on said square portion to cause the notch 28, formed in the bottom side of the housing member flange 26, to pass over the projection 29 which extends outwardly by pressing, or otherwise as desired, from the elevated portion of the base plate 4, when the housing member is pushed downwardly thereover to lock the main shaft against rotation, as will be understood in Figs. 5, 6 and 7. When the housing member is pushed upwardly, with relation to the base plate 4, the notch 28 will move away from the projection 29 and permit the main shaft to be rotated. Fig. 7 shows the housing member in locked position, and Figs. 4 and 5 show it in unlocked position.

Extending inwardly from the elevated wall of the housing member, by stamping or otherwise as desired, at the upper end of the elongated opening or slot 27, is a finger 30 positioned just inside of the finger 24 when the housing member is in its upper unlocked position, as seen in Figs. 5 and 6. Encircling the main shaft, and of substantially larger diameter than the same, is the coil spring 6 having its opposite free ends 31 and 32 bent outwardly and positioned one on one side of the two ears 24 and 30 and one on the other side thereof, as will be understood in Figs. 4, 6 and 7. Due to the width of the elongated rectangular opening 27 being just enough greater than the square portion of the main shaft to permit the housing member to slide laterally on said square portion, it will be understood that rotation of the main shaft will cause the housing member to rotate therewith when in unlocked position. It will also be seen that the finger 24, which is fixed to the base plate 4 which in turn is fixed to the door, is stationary, while the finger 30 is rotatable with the housing member 5. This means that when the main shaft is rotated clockwise as viewed in Figs. 6 and 7, the spring end 32 will be held stationary by finger 24, while finger 30 will move clockwise with the housing member carrying the spring end 31 with it, thus putting the coil spring 6 under a strain that will carry the spring end 31 back against the finger 24 and return the main shaft to its normal neutral position when the turning force is released from the inside handle 2 or the outside knob 3. This will cause the latching nose 33, which is carried by the inner handle 2, to normally stand in mid-position with relation to the striker plate 9, when the door is closed, the main shaft then being in neutral position. Likewise, when the main shaft is rotated counterclockwise, as viewed in Figs. 6 and 7, the spring end 31 will be held stationary by finger 24, while finger 30 will move in a counterclockwise direction and carry the spring end 32 with it, thus putting the coil spring 6 under a strain that will carry the spring end 32 back against the finger 24 and return the main shaft to its normal neutral position, when the turning force is released. This movement of the finger 30 to one side or the other is made possible by the arcuate slot 25 formed in the base plate 4.

In order to releasably hold the housing member 5 in locked and unlocked positions there is provided a detent washer 7 slightly curved in a vertical direction and

formed with a centrally located square hole 34 of a size to fit over the square portion of the main shaft. As seen in Figs. 3 and 5, the detent washer 7 is positioned between the outer elevated face of the housing member 5 and the adjacent end of the hub of the inner turning member 2. On each side of the square hole 34 of the detent washer, in horizontal alignment a short distance below the horizontal center line of the washer, is formed by pressing, or otherwise as desired, a semispherical projection 35 extending toward the housing member. As seen in Fig. 4, there are formed by pressing or otherwise as desired, on the outer adjacent face of the housing member 5, two pairs of depressions 36 and 37, said pairs being spaced apart and so positioned that when the housing member 5 is moved upwardly on the main shaft into unlocking position, the pair of projections 35 on the detent washer 7 will be seated in the pair of depressions 37, see Fig. 4, and when the housing member is moved downwardly into locking position, the pair of projections 35 on the detent washer 7 will be seated in the pair of depressions 36 of the housing member. The curvature of the detent washer 7 is such as to resiliently urge the projections 35 into the respective pairs of depressions in the housing member, and facilitate their removal therefrom, as the housing member is moved to its positions of adjustment for locking and unlocking the main shaft from and for rotation. This prevents the housing member from becoming loose, and from rattling. As will be understood the main shaft will be in mid or neutral position when such movements of the housing member to locking and unlocking positions occur.

The striker plate 9 comprises a supporting frame 38 having a flat base formed with a pair of longitudinally spaced inclined slots 39 through each of which extends a screw 'a' for securing the striker plate to a flat inner face of the door frame 40. The supporting frame 38, at each of its ends, is formed with an upstanding flange 41 each having an inclined outer edge 42, said flanges being of greater depth at the side farthest away from the door, as seen in Figs. 1 and 3. In each of said flanges in its portion of greater depth is formed an arcuate slot 43, which slots are similarly positioned opposite each other. In the opposite side of each of said flanges, and nearer to the door frame, is formed a round hole 44, which holes are similarly positioned opposite each other.

A swing plate 45, positioned between the end flanges 41, has opposite longitudinal edges each curved into a tubular portion, see Fig. 3, one of said tubular portions being in alignment with said round holes 44, and the other tubular portion opening at its two ends opposite said slots 43. The swing plate 45 is connected to the end flanges 41 by means of two U-shaped bent rod members of staple formations. These two bent rod members being alike, only one of them need be described in detail. As seen in Fig. 8, each of these bent rod members comprises an outer end portion 46 bent to form a pair of parallel legs 47 and 48, leg 47 of which is inserted through one of the round holes 44 and forced with a force fit into the tubular portion at one edge of the swing plate, and leg 48 of which is at the same time passed through the slot 43 of the same end flange and forced with a force fit into the tubular portion at the other edge of the swing plate. As will be understood one of these bent rod members will be inserted inwardly as described through one of said end flanges, and the other inserted inwardly as described through the other end flange. This mounts the swing plate 45 for rotation about legs 47 at one longitudinal edge, and for swinging movement at its other longitudinal edge, with a portion of legs 48 riding in said slots 43. Any other suitable means for securing the legs 47 and 48 to the longitudinal edges of the swing plate, may be used as desired.

A spring member is positioned at each end of the swing plate 45 between the plate and the adjacent end flange 41. Each of these spring members is coiled about

the leg 47 two or more times at 49, and then extended at one end in a spring arm 50 to pass underneath and up around the leg 48, and extended at the other end in an arm 51 to bear against the back plate of the supporting frame 38. These spring members are so constructed as to normally yieldably press the legs 48 upwardly to the top of the slots 43, the corresponding edge of the swing plate 45 moving with legs 48. This normally and yieldably holds the swing plate 45 at the angle shown in Figs. 1 and 3, which means that when the door is being moved to closed position, the latching nose 33, when the main shaft is in approximately neutral position, will wipe over the swing plate 45 and swing it to the depressed position shown in dotted lines in Fig. 3, until the latching nose clears the swing plate, which will then, under the influence of the springs 49-51, swing outwardly to the position shown in solid lines in Fig. 3, and thus hold the door closed. The door may be unlatched and opened by manually pressing inwardly upon the high side of the swing plate 45 until it clears the end of the latching nose. The door may also be opened, or latched closed, by turning either the inside or outside handle to rotate the main shaft and swing the latching nose laterally of the striker plate, as shown in dotted lines in Fig. 2. As will be understood, when the inner handle 2 stands in either of the two positions shown in dotted lines in Fig. 2, the coil spring 6, upon release of the turning force upon handles 2 or 3, will return the main shaft 1 to neutral position, and the latching nose 33 to its mid position.

Should it be desired to adjust the position of the striker plate with relation to the door frame, for the purpose of preventing rattling between the latching nose and the striker plate, or providing necessary clearance therebetween, this can be readily and easily done by releasing the screws *a* in the inclined slots 39, moving the striker plate in the direction required for the movement desired, and then tightening the screws.

As stated above, rattling of the door may be prevented by adjusting the striker plate longitudinally through the medium of the screws *a* and the inclined slots 39. As seen in Figs. 1, 3 and 11, I have provided further means for preventing such rattling by adjustably connecting the latching nose 33 to the hub portion of the inner handle 2. As will be understood in Figs. 3 and 11, a circular supporting clamp 52 encircles the hub of the inner turning member 2, preferably in a slightly depressed groove 53, and having its ends bent into a pair of parallel, spaced apart ears 54 between which is clamped, by a pair of bolts 55, the latching nose 33. The contacting edges of the inner end of the latching nose and the adjacent surface of the inner turning member hub, are roughened or serrated at 56 to prevent slipping of one with relation to the other when the bolts 55 are tightened. The holes in the latching nose through which the bolts 55 pass are slotted at 57, or the holes in the parallel ears 54 may be slotted at 58, or both of these parts may be slotted, as desired, to enable adjustment of the latching nose with relation to the hub to which the latching nose is attached. From the above it is clear that rattling of the door may be prevented by loosening the bolts 55, or if desired removing them from their holes or slots, then moving the latching nose to take up any undesired play between the latching nose and the striker plate, and then replacing and tightening the bolts in the adjusted position. With suf-

ficient clearance between the holes and the bolts, such adjustment may be effected by merely loosening the bolts without removing them.

If desired, the knob or handle 3 may have threads formed throughout all or part of its axial bore, to interengage threads 16 of the shaft 1, so that after the knob has been screwed onto the round portion 12 of shaft 1 to the desired degree of adjustment for the particular thickness of the door, and the nut 15 tightened in place thereon, the nut will, in effect, serve as a lock nut, for insuring that the knob and the shaft will rotate together as a unit during operation.

Having described my invention, I claim:

1. A striker plate for latching mechanism, comprising, a supporting base adapted to be secured to a supporting member, an upstanding flange at each end of said supporting base, said flanges having similarly inclined top edges to form higher portions at one side of the supporting base than the other, the higher portion of each flange having a slot, said slots being similar and opposite to each other, the lower portions of said flanges having aligned round holes, a swing plate between said flanges and having a curved tubular edge formed along each of its longitudinal edges, a pair of U-shaped rod members of round cross section each having a pair of parallel legs, one leg of one pair passing through said round hole in one of said flanges and fixed in the adjacent curved tubular edge of the swing plate, and the other leg of the last mentioned pair passing through the slot in the last mentioned one of said flanges and fixed in the adjacent curved tubular edge of the swing plate, the other one of said U-shaped rod members being similarly mounted in the other flange and similarly fixed in the respective curved tubular edges on the swing plate, whereby the swing plate will be fulcrumed along one edge and swing in and out at the other edge, and spring means between the supporting base and the swing plate for normally yieldably urging the swing edge of the swing plate to its outermost position with relation to said slots.
2. A striker plate for door latching mechanism, comprising, a supporting frame having a base member formed at each of its ends with an upstanding flange, a swing plate between said flanges, each of the longitudinal edges of the swing plate having bent-under portions having fixed therein projecting rods arranged two on each of said longitudinal edges, each of said flanges having a hole and a slot spaced from said hole, two of said rods being mounted in said holes for fulcrums, and the other two of said rods being mounted in said slots to swingably ride therein, and spring means for normally urging the swing plate to its outermost position.
